[57] CLAIM

The ornamental design of a swivel chair, substantially as shown and described.

DESCRIPTION

FIG. 1 is a front perspective view of a swivel chair showing my design.

FIG. 2 is a perspective view thereof, as seen from the rear.

FIG. 3 is a front elevational view thereof.

FIG. 4 is a rear elevational view thereof.

FIG. 5 is a side elevational view thereof, the opposite side being a mirror image.

FIG. 6 is a top plan view thereof.

FIG. 7 is a bottom plan view thereof.

FIG. 8 is a front elevational view on a reduced scale of a swivel chair having a modified design which differs from the design shown in FIGS. 1-7 only in that the seat back extends upwardly a greater distance and has a somewhat different shape than the seat back of the swivel chair shown in FIGS. 1-7.

FIG. 9 is a side elevational view of the swivel chair shown in FIG. 7, the opposite side being a mirror image.

FIG. 10 is a rear elevational view thereof.
